United States Patent Office

Des. 203,552
Patented Jan. 25, 1966

203,552

CANDLEHOLDER

Jens H. Quistgaard, Lucerne, Switzerland, assignor to Dansk Designs Ltd., a corporation of New York

Filed Jan. 29, 1965, Ser. No. 83,629

Term of patent 14 years

(Cl. D48—2)

FIG. 1

FIG. 3

FIG. 1 is a side elevational view of a candleholder, showing my new design;

FIG. 2 is a top plan view thereof; and

FIG. 3 is a bottom plan view thereof.

The side not shown has substantially the same appearance as the side shown.

I claim:

The ornamental design for a candleholder, as shown and described.
